UNITED STATES PATENT OFFICE.

KINGMAN N. CATHER, OF CHICAGO, ILLINOIS.

TIE.

1,149,247.

Specification of Letters Patent. Patented Aug. 10, 1915.

Application filed December 1, 1913. Serial No. 804,070.

To all whom it may concern:

Be it known that I, KINGMAN N. CATHER, a citizen of the United States, residing at Chicago, in the county of Cook and State 5 of Illinois, have invented certain new and useful Improvements in Ties, of which the following is a specification.

The present invention relates to a tie utilized in railroads to underlie and form a 10 support for the rail sections, and to provide a means for receiving the rail anchoring devices, etc.

One of the objects of the present invention is to construct the tie with a body of 15 a composition nature and to provide metal reinforcements for said body.

A further object is to provide an open work frame construction which will be placed on the body to give the tie strength and to 20 prevent any danger of splitting or crumbling of the material of which the body of the tie is composed.

A further object is to form said frame of a single piece of metal and of open work 25 construction and to provide in said frame a web on the upper face thereof which will extend beneath the rail sections when the tie is positioned.

Another object of the invention is to provide upwardly extending overhanging 30 flanges from said web portion which will receive the rail anchoring means in certain forms of construction, and in other forms will receive the rail anchor means and a 35 block of cushioning material.

Another object of the invention is to provide metal ends for the tie with an overhanging flange from each end to permit 40 of the use of crow bars or analogous tools for handling the ties or moving the same 45 from position.

Another object of the invention is to so configure the tie as to give it the necessary property of resiliency.

A further object of the invention is to 45 provide means for preventing skidding of the tie during use.

The invention further consists in the features of construction and combinations of 50 parts hereinafter described and claimed.

In the art to which the present invention relates practically all ties now used in railroad construction are formed of wood, the preferred tie being made of white oak, since 55 this wood possesses the elasticity, toughness, etc., which are requisite to a practical tie

for railroad construction, but the life of the tie is relatively short and because of the ever increasing demand for lumber, wood ties of this nature have increased in price 60 and have become difficult to obtain in the quantity necessary for railroad use. The tie of the present invention is constructed along certain mechanical lines whereby it possesses the necessary vibratory property 65 which is present in a wood tie, it is formed of a composition so that the tie is of long life, and the tie when positioned will be held by reason of its configuration against any tendency to skid under the pressure of 70 the trains so that any danger of the tie being thrust out of position and distorting the track is eliminated.

In the drawings: Figure 1 is a section of track in which the tie of the present invention is embodied; Fig. 2 is a longitudinal section through one of the ties shown in Fig. 1; Fig. 3 is a cross section through one of the ties shown in Fig. 1; Fig. 4 is a plan view of the metal frame 80 employed in the construction of tie shown in Figs. 1, 2, and 3; Fig. 5 is a longitudinal section of a modified form of construction; Fig. 6 is a plan view of another modified form of construction; Fig. 7 is a cross section through the form of tie shown in Fig. 6; Fig. 8 is a plan view of a third modified form of tie; and Fig. 9 is a longitudinal section through the form of tie shown in Fig. 8. 90

Referring now to the drawings, and particularly to Figs. 1, 2, 3, and 4, the tie 10 there illustrated consists of a metal frame 11, which frame is composed of side pieces 12, end pieces 13, and top web portions 14 extending between the side pieces 12. The bottom of the frame is open, and the frame is also open at the top, as will be seen by referring to Fig. 4 for the major portion thereof and therefore the frame may be designed as a metal frame of open work construction. This frame is so designed as to enable it to be stamped from a single piece of metal and will be simple and cheap of 105 construction and will possess strength and at the same time not add materially to the weight of the tie, its main function being a binder or reinforcement for the body of the tie preventing the cracking or splitting of the tie by climatic actions or otherwise. 110

The frame at each of its ends is formed of a solid, unbroken, metallic face 15, from

which extends an overhanging flange 16, so that the frame is provided at its ends with a solid unbroken metal face and an overhanging flange which forms in effect a pocket of metal. This is an important feature of the present invention since when the tie is completed this metal pocket constitutes a means for permitting the insertion of a crow bar or similar instrument for the purpose of handling the tie without cracking, splitting, or mutilation of the body of the tie by reason of the application of the crow bar or similar instrument. By this means, therefore, provision is made to allow of application of pressure to the ends of the tie without any danger of a mutilation of the body of the tie, and the ability to apply pressure to the end of the tie renders its handling a much simpler operation than would be true otherwise.

Secured in the ends 15 of the frame are a plurality of longitudinally extending rods 17, which in the construction shown are of a slightly curvilinear nature for giving them additional strength, and the frame is also formed with a series of depending flanged fingers 18. The body 19 of the tie, in the construction shown, is composed of cement or other suitable composition, which is of a character to withstand the actions of weather and to render the tie one of long life. This composition body is applied by a suitable molding operation to the metal frame previously described, and this frame, as will be seen from the drawings, is positioned about the upper end of the body when the tie is completed, and the rods 17 and fingers 18 are embedded in the composition body and serve to reinforce and strengthen the same, and hold it together.

The web portions 14 each have extending therefrom oppositely disposed overhanging flanges 20 which serve to receive plates 21 which are constructed with rail gripping members 22 and these plates, when positioned, act as rail anchors to hold the rail in place. The plates 21 are held in position by means of a key 23, which in the construction shown enters into a notch 24 in the edge of the plate 20, and the key is of right angle formation with one end entering the notch and its other end entering into a hole or recess 25 in the body of the tie. When the rail clamp 21 is in position and the key 23 is forced into place, then the rail clamp becomes locked to the rail tie and becomes in fact a part and parcel of the tie structure. If desired, a cushioning block 26 of wood or other resilient material may be interposed between the plate 21 and the web 14, as shown in Fig. 2, or if desired, the plate may be placed directly upon the web as shown in Fig. 5.

The body of the tie is formed with a centrally disposed depending portion 27 render-

ing the tie of increased transverse thickness at its center and this depending portion in the construction shown in Figs. 1 to 7 inclusive, tapers or decreases in transverse thickness from its center to the edges 28 of such depending portion. At the point of merger of the depending portion with the body of the tie shoulders 29 are produced, and in the construction shown the body of the tie decreases in transverse thickness from these shoulders to the ends thereof. This depending portion performs an important office in the present invention. It lends to the tie the characteristic of vibration. The depending portion serving as a rocker about which the tie can move during the passing of rolling stock over the same. It is a well known fact that locomotives and railroad cars are subjected to a swaying action during the traveling of the same over the road bed, and one of the main advantages in the wood tie is the ability of this tie to give or vibrate in conformity with this swaying. If the tie were of rigid unyielding nature the swaying of the locomotive or other rolling stock would produce upon the same a distinct jarring action which would be detrimental to the mechanism and the life thereof. If the locomotive should during such swaying action encounter a hard unyielding surface the sudden jolting or jarring produced by such contact would soon have a tendency to disorganize the mechanism of the same. Now by the provision of this depending portion I provide a rocker for the tie whereby when the ties are subjected to the shocks incident to the swaying of the rolling stock passing over the track the ties will move in conformity with the sway, so that the rolling stock will not meet a hard unyielding surface, but will meet a surface which will yield to the extent necessary to relieve the locomotive or other rolling stock of the jolt or jar to which it would otherwise be subjected. The amount of vibration which is necessary to relieve the rolling stock of undue jolting is, of course, relatively slight and would not be sufficient in practice to loosen the tie from its foundation and shake it out of place. It is contemplated to place a foundation 30 underneath this depending portion which will be of relatively fine material and solidly tamped and to provide a foundation 31 beneath the remainder of the tie will be of a coarser formation and less solidly tamped, so that the material underneath the ends of the tie can give sufficiently to allow of the vibratory action heretofore described, although what may be termed the seat of the tie which is in reality the foundation portion 30 is sufficiently hard and unyielding to prevent displacement of the tie during use.

The shoulder 29 heretofore referred to

also forms an important part of the present invention. These shoulders provide abutments which engage with the foundation beneath the tie and serves to prevent the tie 5 from skidding under the influence of the strain imparted to the tie by the passing of rolling stock over the same. This is a material feature, since with the use of ties of the present construction unless some such means 10 were used for holding the tie against this skidding action, the tie, owing to its nature would be forced from the position in which it was originally laid, and would distort the rails in a manner which might cause serious 15 accidents. It will be seen that the construction is one which gives to the tie the characteristic of maintaining its position without skidding and at the same time allows of the necessary tipping or vibration of the tie to 20 relieve the rolling stock from undue jarring and jolting when passing over the same.

The form of tie shown in Figs. 6 and 7 differs from the form shown in Figs. 1 to 5 inclusive in that an overhanging flange 32 is 25 provided on the top surface of the frame 11, and in that the center portion of the web 14 is eliminated whereby narrower web portions 33 are produced. In other respects, however, this form is similar to the ones 30 heretofore described and contain the same general characteristics.

The form of tie shown in Figs. 8 and 9 while possessing the same general characteristics as the forms heretofore described 35 differs in its shape, being of greater breadth at its end 34 than at its end 35. This form of tie is contemplated to be employed on curves. The form shown in Figs. 8 and 9 differs also in the following particular: The 40 bottom of the tie is formed with a depending section 36 making the tie of greater transverse thickness at the center thereof. The under face of the tie extends in one direction from this greater point of thickness 45 in a manner to provide a continuous uninterrupted surface 37 which is of curved formation, and thus upon this side of the tie, the tie increases regularly in transverse thickness from its center to its end. The 50 other side of the tie, however, first decreases in thickness from the center to the point 38 and at that point is formed a shoulder 39 and the body of the tie continues from the upper edge of this shoulder to its end in a 55 manner to gradually reduce its thickness from the shoulder to the end of the tie. Thus only one shoulder is employed in this construction. It will be remembered that this construction is to be used on curves or 60 alternated on straight tracks and this shoulder is formed to lie toward the outer edge of the curve and will serve to resist the thrust and weight of momentum exerted upon the rails at curves which is always toward 65 the outer side of the curve. Practi-

cally no strain is exerted tending to force the tie toward the inner side of the curve, and hence the necessity for preventing skidding in this direction is not necessary.

It is to be understood that I do not desire to limit myself to any particular form of material which will constitute the body of the tie but intend to cover the use of such material or materials as would be practical for the purpose intended, and in general I do not limit the invention to structural details in any other manner than may be created by the terminology of the appended claims.

I claim:

1. A rail tie formed of a metal frame and a composition body, said frame being formed of metal side and end pieces and webs between the side pieces and arranged to underlie the rails and lie on the top of the body, substantially as described.

2. A rail tie formed of a metal frame and a composition body, said frame comprising metal side and end pieces, webs between the side pieces arranged to underlie the rails and lie on the top of the body overhanging flanges extending from said webs and positioned to lie on either side of the rail sections, said flanges constituting a frame to receive a rail anchoring device, substantially as described.

3. A rail tie formed of a composition body, said body being constructed with a central depending portion, shoulders formed at the point of juncture of the depending portion with the body of the tie, said depending portion decreasing in a transverse thickness from the center to the ends thereof, substantially as described.

4. A rail tie formed of a composition body, said body being constructed with a central depending portion, shoulders formed at the point of juncture of the depending portion with the body of the tie, said depending portion decreasing in transverse thickness from its center to said shoulders and said body decreasing in transverse thickness from said shoulders to the ends of the tie, substantially as described.

5. A rail tie formed of an open-work metallic frame and a composition body, said body being constructed with a central depending portion and shoulders formed at the point of emergence of the depending portion with the body of the tie, substantially as described.

6. A rail tie formed of an open-work metal frame and a composition body, said body being constructed with a central depending portion, shoulders formed at the point of juncture of the depending portion with the body of the tie, said depending portion decreasing in transverse thickness from its center to said shoulder, substantially as described.

7. A rail tie formed of an open-work metal frame and a composition body, said body being constructed with a central depending portion, shoulders formed at the 5 point of juncture of the depending portion with the body of the tie, said depending portion decreasing in transverse thickness from its center to said shoulders and said 10 body decreasing in transverse thickness from said shoulders to the ends thereof, substantially as described.

8. A rail tie comprising a body, an open-work metal frame on said body comprising sides and end pieces and webs between the 15 side pieces arranged to lie on the top of the body and beneath the rail sections, substantially as described.

9. A rail tie formed of an open work metal frame, a composition body and said 20 frame having the entire outer surface thereof exposed and said frame extending about the top, ends and upper side portions of the body, substantially as described.

10. A rail tie comprising a body, a one-piece metal frame arranged to form a cap 25 for said body, members on said frame and integral therewith and adapted for the reception of a rail anchoring device, said tie body being formed with a hole adjacent 30 each of said members, and said members each being formed with a hole co-operating with one of said tie holes to receive locking means for said rail anchoring devices, substantially as described.

11. A rail tie formed of a single-piece, 35 stamped-metal frame, a composition body and said frame having the entire outer surface thereof exposed when positioned on said body and said frame extending about 40 the top, ends and upper side portions of the body, substantially as described.

12. A rail tie formed of an open work metal frame comprising side, end and top pieces, a composition body and said frame 45 being configured to provide metal ends for the tie, the sides and top of the frame being extended to provide a metal pocket at the ends of the tie having top, side and back walls, substantially as described.

13. A rail tie formed of a single-piece 50

stamped-metal frame comprising side, end and top pieces, a composition body and said frame being configured to provide metal ends for the tie, the sides and top of the frame being extended to provide a metal 55 pocket at the ends of the tie having top, side and back walls, substantially as described.

14. A rail tie formed of a single piece, stamped-metal frame, a composition body, 60 said frame extending about the top, ends and upper side portions of the body and having the entire outer surface thereof exposed when positioned upon the body and said body being formed with a centrally disposed 65 depending portion constituting a rocker for the tie, substantially as described.

15. A rail tie formed of an open-work metal frame, a composition body, said 70 frame extending about the top, ends and upper side portions of the body and having the entire outer surface thereof exposed when positioned on the body, said body being formed with a centrally disposed depending portion constituting a rocker for 75 the tie, substantially as described.

16. A rail tie comprising a body, and a metal open work frame extending about the top, ends and upper side portions of the body and having the entire outer 80 surface thereof exposed when positioned upon the body, substantially as described.

17. A rail tie comprising an open work metal frame, formed of top, side and end pieces, a body, said frame being configured 85 to provide metal ends for the tie, the top and sides of said frame being extended to form a metal pocket at each end of the tie having top, side and rear walls, substantially 90 as described.

18. A rail tie comprising a body, and a pressed metal, single piece open work frame on said body, said frame having its entire outer surface exposed and extending around the top, end and upper portions of 95 the body, substantially as described.

KINGMAN N. CATHER.
